LIQUID COOLED ABRASIVE GRINDER

Warren M. Mansfield and Albert W. Olliff, Jr.,
Glendale, Calif.

Application April 13, 1953, Serial No. 348,482

4 Claims. (Cl. 51—267)

The invention relates to a liquid cooled grinding wheel. Heretofore diamond wheels have been used to grind tools of tungsten carbide. However such wheels are expensive. A cheaper wheel, known as a green or silicon carbide wheel, is used as the thick wheel according to the present invention. This type of wheel requires a liquid coolant to prevent glazing the wheel or burning the tool. It is not satisfactory to simply pour or drop a liquid coolant on the face of the wheel because water does not get behind the tool to the surface which is being ground and where the heat is actually generated by friction.

An object of the invention is to provide a grinding wheel supplied with liquid, which may be the usual emulsion of oil in water to cool a tool or other article being ground by the wheel by means of mist formed by supplying the liquid through the pores of a thick wheel or along the side of a thin wheel by centrifugal force due to rotation of the wheel.

Thin grinding wheels are useful to reduce the web on a drill, or to cut the chip breaker groove on a tool.

A further object of the invention is to provide a construction involving parts which may be added to an existing motor driven grinding wheel to convert the same to a wet grinder. This is accomplished by providing cup members having outer flanges at opposite sides of the central portion of the wheel, with a seal between the outer margin of each flange and the wheel to provide a chamber in each cup member and by leading the liquid coolant into the chambers, whereby the rotation of the grinding wheel draws the liquid out of such chambers through the pores of the wheel.

In the preferred form of the invention machine shop work is not required to provide a conduit in the shaft and hence the invention may be applied to existing dry grinders in the field, by providing a nut with abaxial passages and associated parts for leading the liquid coolant into the chambers along the outside of the shaft, the nut serving also to clamp the cup members and the grinding wheel together. It has been found that the side of the wheel which is adjacent the inlet for the liquid coolant withdraws the major portion of the liquid coolant, with only a minor portion, if any, going to the far side of the grinding wheel. According to the invention, the distribution of the liquid coolant in the wheel is equalized by providing a gasket for the cup member at each side of the wheel, the gasket at the inlet side of the wheel covering a larger amount of the central portion of the wheel than the other gasket so as to equalize the flow of liquid coolant into the wheel.

For further details of the invention reference may be made to the drawings wherein:

Fig. 1 is a vertical sectional view of a modification wherein the liquid coolant is fed to the grinding wheel without using an axial hole in the shaft.

Fig. 2 is a view in elevation looking at the outer end of the device of Fig. 1, the view being partly in section and part of the wheel being broken away.

2

Fig. 3 is a sectional view on line 3—3 of Fig. 1.

Referring to Fig. 1, the liquid coolant is supplied by a pipe, not shown, this pipe having a sliding fit in socket 57 in a hollow nut 58. Nut 58 has flat surfaces like 59 and 60, see Fig. 2, to receive a wrench to screw the nut in place, the nut having an axial thread bore 61 for the threads 62 on the outer end of the shaft 63. The annular margin 64 at the inner end of the nut bears against the outer flat portion 65 of the cup member 66 so as to force its flange 67 against the grinding wheel 68, with an intervening gasket 69 cemented to the wheel by rubber cement indicated at 70. The gasket 69 extends inwardly to cover a major portion of the central portion 71 of the wheel within the cup 66, leaving a small exposed portion 15 72 which receives the liquid coolant. Shaft 63 has a sleeve abutment 73 for the flat end 74 of a cup member 75 at the inner side of the wheel. Cup member 75 has a flat annular flange 76 as provided for on the other cup member, flange 76 having a gasket 77 cemented to the wheel 68 by rubber cement indicated at 92. Gasket 77 is narrow so as to leave all of the central portion 93 at the inner side of the wheel exposed to the liquid coolant in cup 75. By having gasket 69 extend over a larger portion at the center of the wheel than the 20 gasket 78, the flow of coolant through the wheel 68 is equalized.

The reservoir 79 in cup member 66 and the reservoir 80 in cup member 75 are in communication by channels like 81, four being shown through the lead bushing 82 30 at the hub of wheel 68.

The coolant flows through nut 58 as follows. The nut 58 is bored or machined outwardly of the outer end of threads 61 to provide an annular chamber 83 which communicates with the axial socket 57 in the outer end 35 of the nut, leaving an internal annular wall 84 drilled lengthwise to provide one or more ab-axial longitudinal passages, two being shown, like 85 and 86, the outer ends like 87 of these passages opening into the chamber 83. The inner ends like 88 of the passages like 85 and 86 40 open into an annular chamber like 89 in the inner end of the nut, and this chamber opens into two or more holes like 90 and 91 through the wall of cup member 66, the passages 90 and 91 opening into reservoir 79. The socket 57 and the chamber or transverse passage 45 83 with the abaxial passages 85 and 86 thus lead the liquid coolant around the outer end of the shaft 63, whereby it is unnecessary to provide a passage in the shaft.

The form shown in Figs. 1 to 3 has the advantage that a dry grinder in the field can be changed over to a 50 wet grinder without removing the grinder to a machine shop for special machine operations, as it is only necessary to assemble the parts shown and clamp them in position by means of nut 58. Of course a suitable reservoir and associated parts including a supply pipe must be provided.

Various modifications may be made in the invention without departing from the spirit of the following claims.

We claim:

1. In cooling means for abrasive cutters including a 60 grinding wheel having a shaft, the improvement which comprises a cup member coaxial with said shaft at each side of the wheel, each of said cup members having an outer flange, a gasket between the outer margin of each of said flanges and the wheel, each of said members providing a chamber at the central portion of the wheel, said shaft having an abutment and having an outer end having threads, a hollow nut for said threads for clamping said cup members and said wheel together against said abutment and conduit means including a passage extending through said nut and connecting with said chambers for supplying a liquid coolant to said chambers, one of said cup members being an outer cup member adjacent said

nut, the extent of said gasket for said outer cup member over the inner portion of the outer side of said wheel being greater than the extent of said other gasket over the central portion of the other side of said wheel to equalize liquid intake by said wheel.

2. In cooling means for abrasive cutters including a grinding wheel having flange members and a shaft having an abutment, with a pipe for supplying a liquid coolant, the improvement which comprises a nut for clamping said flange members and said wheel together on said shaft against said abutment and for supplying liquid coolant from said pipe to the wheel, said nut comprising a socket for said pipe, said nut having an internal wall having a bore having threads for said shaft, said internal wall having longitudinal fluid passages therein outside of the threads of its said bore and a transverse fluid passage in said nut connecting said socket and said longitudinal passages.

3. In abrasive cutters, a combined clamping and coolant fluid conducting nut comprising a pipe socket at one end of said nut, said nut having an internal wall having an axial bore having threads, said internal wall having longitudinal fluid passages therein outside of the threads of said bore, and a transverse fluid passage in said nut connecting said socket and said longitudinal passages.

4. In abrasive cutters according to claim 3, in combi-

nation with cup members adapted to be clamped by said nut on opposite sides of a grinding wheel, each of said cup members having a chamber for a liquid coolant for the wheel, and connections between said chambers and said longitudinal passages.
